(57) CLAIM

The ornamental design for a snake plunger, as shown.

DESCRIPTION

FIG. 1 is a perspective view of a snake plunger showing my new design;

FIG. 2 is a front plan view thereof;

FIG. 3 is a top plan view thereof; and,

FIG. 4 is a bottom plan view thereof.

Note that the rear plan view and side plan views are substantially similar to the front plan view of FIG. 2, and have not been included herein.
